UNITED STATES PATENT OFFICE.

JOHN J. CLINE, OF ALIX, ARKANSAS.

TONGS.

Application filed November 7, 1927. Serial No. 231,612.

This invention aims to provide a simple but efficient tool whereby the battery terminal may be loosened, when it has become corroded on the post of the battery, or when 5 the clamping bolt in the battery terminal has become corroded in its place.

It is within the province of the disclosure to improve generally and to enhance the utility of devices of that type to which the 10 invention appertains.

With the above and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without 20 departing from the spirit of the invention.

In the drawings:—

Figure 1 shows in side elevation, a tool constructed in accordance with the invention;

25 Figure 2 is a detail enlarged from Figure 1;

Figure 3 is a section on the line 3—3 of Figure 2, remote parts being omitted, and the tool being shown in place in operative 30 position on the terminal of a battery; and

Figure 4 is an elevation showing one of the jaws.

The tool for loosening battery terminals, shown in this application, comprises levers 35 1 and 2 which are crossed upon each other as at 3, and connected pivotally at their place of crossing, by a pivot, bolt, or other pivot element 4. The lever 1 has a jaw 5 and the lever 2 has a jaw 6, the jaws 5 and 6 cooperating in a way which will be described hereinafter. The jaw 6 has a substantially flat surface 7. The jaw 6 has lateral grooves 8 and 9, which converge and intersect the flat surface 7, to form an edge 10.

45 The groove 9 in Figure 3 is shown as receiving the end 11 of the clamping bolt 12 in a battery terminal 14, and the groove 8 is shown as receiving one corner 15 of the nut 16 on the bolt 12. The grooves 8 and 9 are

50 of like construction, to provide for a re-

versal of the tool; that is, if the bolt 12 happens to be turned end for end from the position of Figure 3 it may be expedient to receive the end 11 of the clamping bolt 12 in the groove 8, and to receive the corner 15 of the nut 16 in the groove 9, the jaw 5 then engaging the arm 21. The jaw 5 has a chisel edge 17 for acquiring a hold on the inclined surface 18 of one arm 19 of the battery terminal 14. In the event that the nut 16 happens to be of such shape, or happens to be turned into such a position, that the corner 15 is not received in the groove 8, then the flat surface 7 of the jaw 6 may bear against the nut. When the jaws 5 and 6 are moved toward each other, after the nut 16 has been backed off a little, as shown in Figure 3, the arm 19 will be moved lengthwise of the bolt 12, thus spreading the arms 19 and 21 apart. This loosens the terminal from the post 20, 70 but the bolt 12 remains stuck in the arm 21. It is a good plan to leave the bolt 12 stuck in the arm 21 because then the bolt will not rotate when the nut 16 is turned up tight again, and a person does not have to hold 75 the bolt with a wrench. The edge 10 is adapted to be received in the angle between the end 11 of the clamping bolt 12 and the outer surface of the nut 16, as shown in Figure 3.

80 What is claimed is:—

A tool for loosening battery terminals, comprising pivotally connected levers provided with cooperating jaws, one jaw having a substantially flat surface, and having 85 grooves which converge and intersect said surface, one groove being adapted for the reception of the end of the clamping bolt in a battery terminal, the other groove being adapted for the reception of one corner of the nut on the bolt, the grooves being of like construction to provide for a reversal of the tool, the other jaw having a chisel edge for acquiring a hold on the inclined surface of one arm of a battery terminal.

90 In testimony that I claim the foregoing as my own, I have hereto affixed my signature.

95 JOHN J. CLINE.
